Application April 13, 1935, Serial No. 16,186

12 Claims. (Cl. 200—38)

The invention relates generally to circuit breakers and more particularly to mechanisms for actuating the cooperative switch members of circuit breakers.

- 5 An object of the invention is to provide a quick acting multiple pole circuit interrupter that will respond to abnormal circuit conditions in the switch members of any pole to trip the switch members of all the poles.
- 10 It is also an object of the invention to provide for the independent operation of the switch members of any pole of a multiple pole circuit breaker upon the development of abnormal circuit conditions to interrupt the circuit through the switch members of that pole, and to effect the operation of the switch members of the other poles, in quick succession to the actuation of the switch members operated in response to the abnormal circuit conditions, to interrupt the circuits through the switch members of all the poles.
- 15

20 Other objects of the invention will in part be obvious and will in part appear hereinafter.

25 The invention accordingly is disclosed in the embodiment thereof shown in the accompanying drawing and comprises the features of construction, combination of elements and arrangement of parts which will be exemplified in the construction hereinafter set forth and the scope of the application of which will be indicated in the claims.

30 For a fuller understanding of the nature, and objects of the invention, reference should be had to the following detail description taken in connection with the accompanying drawings, in which

35 Figure 1 is a perspective view of the actuating mechanism of a circuit breaker constructed in accordance with this invention.

40 Fig. 2 is a view in side elevation of the circuit breaker illustrated in Fig. 1 showing how the members of the mechanism are disposed relative to one another.

45 Fig. 3 is a view, in front elevation, of the actuating mechanism of the circuit breaker showing the relation of the members.

Referring now to the drawings and Figs. 1 and 2 in particular, the circuit breaker or interrupter comprises a cast iron frame, indicated generally by the numeral 15, provided with cross members 16 that may be utilized for attaching it to a switchboard 17 and a plurality of supporting members, the functions of which will be set forth herein-after as the structure of the breaker is described. While a cast frame 15 is illustrated, it is to be understood that a fabricated frame may also be employed.

As best shown in Fig. 2, the cross members 16 of the circuit breaker frame 15 are attached to the switchboard 17 by means of bolts 18 in accordance with standard practice. The switchboard 17 is preferably made from marble, slate or some other material commonly employed in switchboards. In the present breaker structure many standard parts are employed, such as an arc interrupter 19, switch-arm structure 20 and tripping mechanism 21.

In the present structure, the arc interrupter 19 is of the type in which the arc is rotated between spaced plates, as shown for example in Brainard Patent No. 1,896,764, issued February 7, 1933, and therefore a detailed description of it will not be included. As illustrated, the arc extinguisher is mounted on the switchboard 17 by means of screw bolts 12.

35 The switch-arm 20 which has been employed heretofore in such structures, comprises a cast iron member 22 pivotally connected at 23 to a bracket or support 24 carried by the switchboard 17. As illustrated, a projection 25 is provided 40 on the lower end of the member 22 and shaped to receive the end of a coil spring 26. The other end of the spring is connected to a projection 27 provided on the support 24.

45 The spring 26 being in tension biases the member 20 to the position illustrated in Fig. 2. This spring cooperates in the operation of the switch-arm, as will be explained hereinafter. A plurality of copper blocks 28 and 29 are supported on the switch member 22 by means of bolts 30 and 31, respectively. Coil springs 32 and 33 are mounted on the bolts 30 and 31, respectively, and bias the copper blocks 28 and 29 away from the switch-arm 22. Contact members 11 are provided on the blocks 28 and 29 and disposed to align with con-

35

40

45

50

55

55

tact members 34 carried by a copper bus 35. As illustrated, the bus is bolted to the switchboard 17.

In order to connect the contact members 28 and 29 in a circuit, flexible shunts 36 and 37 which are electrically connected with the bus 38 are provided. The flexible shunts engage in notches provided in the lower ends of the blocks 28 and 29 and cooperate with the bolts 30 and 31 in supporting the contact members 11 in alignment with the contact members 34.

In the breaker illustrated, a stationary conductor 39 extends between the bus 38 and a member which is electrically connected to a plate of the arc interrupter 19. This conductor and member 40 are employed, in accordance with well known practice, to carry current during the arc interrupting process.

A shunt 41 extends between the shunt 36 and the arc tip 42 shown in dotted lines. These members are also employed in accordance with standard practice and function to maintain a circuit to the arc interrupter during a switching operation. The shunt 41 and arc tip 42 constitute a comparatively high resistance circuit.

The mechanism of the breaker or interrupter illustrated is for actuating the switch members of a multiple pole unit. In this instance it is shown applied to operate a three-pole switch such as may be employed for interrupting a three-phase circuit, but it is to be understood that other applications of this mechanism may readily be made by following the teachings of this invention.

Referring to Fig. 1 in particular, the switch actuating mechanism is illustrated as applied for operating the cooperative switch members of a three-pole switch. In order to simplify the drawings, only the switch arms 43, 44 and 45 of the switch units are shown. Each switch unit represented by the switch arms 43, 44 and 45 will be similar to the one disclosed in Fig. 2 and described hereinbefore. Therefore, as the description of the mechanism proceeds, it will be understood that when reference is made to the switch-arms 43, 44 and 45, it is intended to mean switching units similar to that of Fig. 2.

In mounting the switching units of the different poles, they are separated by barriers 46 made from suitable insulating material. These barriers will prevent arcing between the switch units under abnormal voltage conditions.

Three toggle linkages 47, 48 and 49 are provided for the switch members 43 to 45, inclusive, respectively. These toggle linkages are pivotally connected to the switch-arms 43 to 45, inclusive, as shown at 50. The toggle linkages employed in this particular embodiment of the invention each include two links of substantially equal length pivotally connected.

In order to support the toggle linkages so that they may be utilized for operating the switch arms 43, 44 and 45, three arms 51, 52 and 53 are provided. The arm 52 performs an additional function to the arms 51 and 53 and for that reason will be referred to as a supporting arm. As illustrated, the three arms are pivotally connected to V-shaped brackets 54 and 55 provided on the frame 15.

The arms 51 and 53 are of the same size and shape and are pivotally connected at 56 and 57 to the upper arms of the V-shaped brackets 54 and 55, respectively. The pivotal connections to the bracket are disposed at about the centers of the arms 51 and 53.

The supporting arm 52 illustrated in Fig. 8 is substantially triangular in shape being provided

with spaced members at the base which are pivotally connected at 58 to the lower arms of the V-shaped brackets 54 and 55.

The upper ends of the arms 51 to 53, inclusive, are pivotally connected at 59, 60 and 61 to the outer ends of the toggle linkages 47 to 49, inclusive, respectively. As shown, the upper ends of the arms 51 to 53, inclusive, are bifurcated to receive the outer members of the toggle linkages and facilitate the making of the pivotal connections.

In order to balance the reactive pressures received from the switch members through the toggle linkages 47 to 49, inclusive, against one another, a balancing lever 62 is pivotally mounted on the supporting arm 52 at 63. As illustrated, the pivot point 63 is approximately midway between the pivotal connections 58 and 60.

The balancing lever 62 is best illustrated in Fig. 5 and is provided with two arms 64 and 65. The arms are spaced angularly around its pivotal axis.

As shown, the length of the balancing lever along its pivotal axis is substantially that of the spacing of the arms 51 and 53. The purpose of making this long lever is to align the arms 64 and 65 with the arms 51 and 53, respectively.

Referring to Fig. 1, the arms 64 and 65 of the balancing lever are pivotally connected by links 66 and 67 to the arms 51 and 53, respectively. The links 66 and 67 are of the same size and shape.

In order to actuate the toggle linkages to move the switch arms 43 to 45, inclusive, to their closed positions, extensions 68 are provided on the outer members of the linkages 47 to 49, inclusive. These toggle linkages 47 to 49, inclusive, may be actuated in any suitable manner as by a lever or an electromagnet. In the present instance, the extensions 68 are connected through links 69 to 70 pivoted at 13 for manually operating the linkages to their in-line or switch closing positions and an electromagnet 71 connected to the lever for effecting a power operation.

A spring 14 is provided for biasing the lever 10 and the armature of the electromagnet 71 to predetermined positions where they stand inactive and permit the tripping of the breaker.

The electromagnet 71 may be operated in any well known manner at the will of an operator and means for energizing it are not illustrated.

A tripping device is provided in conjunction with each toggle linkage. The tripping mechanism is best illustrated in Fig. 2 and comprises a depending rod 72 connected to the outer members of the linkages at a point almost directly below the linkage joints when they stand in their in-line positions as when the switches stand in their closed positions.

In order to exert a downward pull on the rods 72 to trip the linkages together or independently, bell cranks 73 are provided. As illustrated, each bell crank is pivotally mounted at 74 on projections 75 provided on the frame 15. One arm of each bell crank is pivotally connected to a rod 72. When circuit interrupters or breakers of this kind are utilized in electric power systems, it may be desirable to effect their operation when abnormal circuit conditions develop. For example, it may be desirable to operate the breaker 70 upon predetermined overload conditions either of current or voltage or when the circuit breaker is used in a network it may be desirable to trip it upon, the occurrence of a reverse power flow.

In the present embodiment, electromagnets 76

are provided which may be connected in any well known manner to respond to predetermined abnormal circuit conditions. These electromagnets will function to operate the armatures 17 5 carried by the bell cranks 13. In this manner any one or all of the toggle linkages 47 to 49, inclusive, may be actuated.

In addition to the electromagnetic means provided for tripping the linkages, a manually operable lever 18 may be provided for tripping one 10 of the linkages. As illustrated, this manually operable lever 18 is biased to a predetermined position by a coil spring 79. A dog 80 is provided on the inner end of the manually operable lever 18 15 in alignment with a latch 81 carried by the rod 72. When the linkages stand in their in-line position with the switches closed, the latch 81 engages the dog 80. Consequently, if it is desired to trip the breaker manually the lever 18 is 20 raised and a downward pull may be exerted on the rod 72 which will trip the linkage. As will be explained hereinafter, when any one linkage is tripped, the breaker as a whole is tripped.

Referring again to Fig. 1, a bar 82 having a 25 plurality of downwardly extending members 83, 84 and 85 is carried by webs 86 formed integral with the frame 15. These members 83 to 85, inclusive, are disposed in alignment with the linkages 47 to 49, inclusive. Each member 83 to 30 85, inclusive, is provided with a cam face 87 which cooperates with a corresponding cam face 88 provided on the linkages 47 to 49, inclusive, to trip the latter when they move outwardly in a manner that will be described hereinafter.

35 On the back of the bar 82 a plurality of bumpers 89 are disposed in alignment with the switch arms 43 to 45, inclusive. These bumpers receive the switch arms when the circuit breaker is opened.

40 Assuming now that the circuit breaker is connected in a three-phase network system, and that the magnet 76 is adapted to respond to what is generally termed "reverse power flow" in any pole of the breaker, and that the breaker stands in 45 its open position, then to establish circuit connections, the breaker is actuated either manually through lever 70 or by means of the magnet 71, to move the switch members into circuit closing positions, if the lever is pulled downwardly, the 50 toggle linkages are moved upwardly to their over-center positions and the movable switch contact members 33 are moved into engagement with the stationary switch contact members 34. The springs 32 and 33 which are employed to give the 55 desired contact pressures between the switch contact members 33 and 34 make it possible to move the toggle linkages to their over-center positions.

The reactive pressures resulting from the biasing of the switch contact members into pressure engagement are transmitted through the 60 toggle linkages to the arms 51 to 53, inclusive. The reactive pressures received by the arms 51 to 53, inclusive, are balanced against one another.

65 Referring now to Fig. 1, the reactive pressure transmitted to arm 53 biases it counter-clockwise about its pivot point 51. This biasing force is transmitted through link 67 to the arm 65, biasing the balancing lever 62 counter-clockwise 70 about its pivotal mounting 63. The reactive pressure transmitted to the arm 51 applies a biasing force counter-clockwise about its pivot point which is transmitted through links 66, arm 64, biasing the balancing lever clockwise about its 75 pivot point 63.

From the foregoing, it will be clear that the reactive pressures delivered through the arms 51 and 53 to the balancing lever 62 will set the balancing lever in a predetermined position on its pivotal axis 63 where the reactive pressures are 5 in equilibrium. The balanced reactive pressures will bias the supporting arm 52 clockwise about its pivot points 58 which are in line. The biasing force applied to the supporting arm 52 through the balancing lever 62 is opposed by the reactive 10 pressures received through the toggle linkage 48. The reactive pressure transmitted directly from the switch members 44 is in opposition to the biasing force applied to the pivot point 63.

The reactive pressure received from one switch 15 unit is opposed to the reactive pressures received from the other two switch units. In order to obtain a balanced condition and state of equilibrium between the reactive pressures received from the switch units, the satisfactory pivotal connections 20 of the arms on the frame are so positioned relative to the line of action of the reactive forces that the reactive force delivered to the supporting arm 52 will balance the reactive forces delivered through the arms 51 and 53 to the supporting arm 52 through the balancing lever 62.

In this manner, when the switch is closed, the contact members of the switch units are held in pressure engagement. The means for retaining the contact members in pressure engagement is 30 in the nature of a system of floating levers.

Assuming now that abnormal circuit conditions develop and that an electromagnet 76 is energized, effecting the operation of the armature 17, then a rod 72 is drawn downwardly tripping 35 a toggle linkage. As soon as one toggle linkage is broken, the whole breaker is immediately tripped.

In order to explain the operation in response to the tripping of one linkage, we will assume that 40 the toggle linkage 49 is the one that has been tripped in response to abnormal circuit conditions. As soon as the toggle linkage 49 is broken, the arm 53 will no longer balance the reactive pressure delivered to the balancing lever 62 45 through the arm 51. The reactive pressure delivered from the switch unit 43 to the arm 51 will rotate this arm counter-clockwise about its pivot point 56 and the balancing lever clockwise about its pivot point 63.

The toggle linkage 47 will move outwardly when its support is removed, and its cam face 88 will be projected into engagement with the cam face 87 and the member 83. These cam faces are so designed that as the linkage moves outwardly, it 55 will be broken and the switch-arm 43 will be projected outwardly by springs 32, 33 and 26.

When the reactive pressure applied to the balancing lever 62 through the arm 53 is released, the floating levers are no longer in a state of 60 equilibrium and the supporting arm 52 responding to the reactive pressure from the switch-arm 44 is caused to rotate counter-clockwise about its pivot points 58. The result of this is that the linkage 48 moves outwardly and its cam face 88 65 engages the cam face of the member 84 with the result that this linkage is also broken.

From the foregoing, it will be evident that when the toggle linkage supporting the switch contact members of any pole in pressure engagement is broken that the other toggle linkages will immediately be moved outward and broken by the corresponding members 83 to 85, inclusive.

From the foregoing, it will be obvious that when abnormal circuit conditions develop and the 75

switch members of any one pole of the breaker are actuated to interrupt the circuit through that pole, then all of the switch members of the other poles will be operated immediately to operate the breaker to its open circuit position.

I claim as my invention:

1. In a multiple pole circuit breaker, in combination, a plurality of cooperative switch members, means for actuating the cooperative switch members of each pole into pressure engagement, the actuating means having fixed pivot points, a balancing lever pivotally connected to the actuating means of the cooperative switch members of the different poles, for balancing the reactive pressures from the switch members for the different poles about the pivot points of said actuating means to retain the cooperative switch members of the different poles in pressure engagement.

2. In a multiple pole circuit breaker, a plurality of cooperative switch members for each pole, means for actuating the switch members to perform switching operations, members having fixed pivot points operable to support the switch actuating means to maintain the cooperative switch members in pressure engagement and means connected to the pivoted members for balancing the reactive pressures received from the switch members for the different poles about the pivot points of said pivoted members thereby to retain the cooperative switch members of the different poles in pressure engagement.

3. In a multiple pole circuit breaker, in combination, a plurality of cooperative switch members, pivotally mounted arms connected to one of the cooperative switch members of each pole, a balancing lever pivotally connected to the arms and operative to retain the cooperative switch members in pressure engagement, the points of the connections between the arms and the balancing lever being so disposed relative to the pivot points of the arms that the reactive pressure from the contact members received by one arm is balanced against the reactive pressure received from the contact members by the other arms whereby if the pressure transmitted through one arm is released, movement of all the arms is effected to operate the breaker.

4. In a multiple pole circuit breaker, in combination, a plurality of cooperative switch members, pivotally mounted arms connected to one of the cooperative switch members of each pole, a balancing lever pivotally connected to the arms and cooperative to retain the switch members in pressure engagement, the points of the connections between the arms and the balancing lever being so disposed relative to the pivot points of the arms that the reactive pressure from the contact members received by one actuating arm is balanced against the reactive pressure received from the other actuating arm, thereby if the pressure transmitted through one arm is released, the movement of all the arms is effected and means cooperative to effect the opening of the breaker when the arms move in response to the releasing of one of the arms from the reactive pressure transmitted from the corresponding contact members.

5. In a multiple pole circuit breaker, in combination, a plurality of cooperative switch members, toggle linkages connected to the cooperative switch members of the different poles for operating them, pivotally mounted arms connected to the toggle linkages, a balancing lever pivotally connected to the arms and cooperative to retain the switch members of the different

poles in pressure engagement, the points of connections between arms and balancing lever being so disposed relative to the pivot points of the arms that the reactive pressure from the contact members received by one arm is balanced against the reactive pressure received by the other arms, whereby if the pressure transmitted through one arm is released, movement of all the arms is effected and means cooperative with the toggle linkages to break them as they move thereby to operate the breaker.

6. In a multiple pole circuit breaker, in combination, a plurality of cooperative switch members, a pivotally mounted arm for the cooperative switch members of each pole of the breaker, the pivotally mounted arms being disposed for retaining the cooperative switch members in pressure engagement, a balancing lever pivotally connected to the pivoted arms, the points of the connections between the arms and the balancing lever being so disposed relative to the pivot points of the arms that the reactive pressures from the contact members are balanced against one another when the breaker stands closed.

7. In a multiple pole circuit breaker, in combination, a plurality of cooperative switch members, a pivotally mounted arm for the cooperative switch members of each pole of the breaker, the pivotally mounted arms being disposed for retaining the cooperative switch members in pressure engagement, a balancing lever pivotally connected to one of the arms at a distance from its pivot point, the balancing lever also being connected to the other arms the points of connection being so disposed that the reactive pressures are balanced about the pivot point of the balancing lever and said one arm and disposed to apply a force in opposition to the reactive force of the contact members applied to the actuating lever to which the balancing lever is pivoted when the breaker stands closed.

8. In a multiple pole circuit breaker, in combination, a plurality of cooperative switch members, a pivotally mounted arm for the cooperative switch members of each pole of the breaker, a toggle linkage disposed between each arm and the corresponding contact members, a balancing lever pivotally mounted on one of the arms, means connecting the balancing lever to the other arms, the other arms being disposed to balance about the pivotal axis of the balancing lever, the pivotal axis of the arm carrying the balancing lever and the pivotal axes of the other arms being so disposed relative to one another and to the pivotal axis of the balancing lever that when the breaker stands closed, the pressure is distributed in a predetermined relation between the cooperative contact members.

9. In a multiple pole circuit breaker, in combination, a plurality of cooperative contact members, a toggle linkage connected to the cooperative contact members of each pole, means for actuating the toggle linkages of the different poles to their over-center positions, a plurality of levers pivotally connected to the toggle linkages to support them to cooperate in the actuating into engagement of the contact members of the different poles of the breaker when the toggle linkages are actuated to their over-center positions, a balancing lever pivotally mounted on one of the supporting levers and pivotally connected to the other supporting levers, the pivotally connected levers being balanced about

- the pivotal axis of the balancing lever and disposed to apply a reactive force received from the corresponding contact members through the axis of the balancing lever which is opposed to the reactive pressure from the contact members transmitted through the supporting lever carrying the balancing lever whereby the pressures between the contact members are distributed from one pole to the other.
10. In a multiple pole circuit breaker, in combination, a plurality of cooperative contact members, a toggle linkage connected to the cooperative contact members of each pole, means for actuating the toggle linkages of the poles to their over-center positions to move the cooperative contact members into pressure engagement, a plurality of levers pivotally connected to the toggle linkages to support them to cooperate in the closing of the contact members of the different poles of the breaker when the toggle linkages are actuated to their over-center positions, a balancing lever pivotally mounted on one of the supporting levers and pivotally connected to the other supporting levers, the pivotally connected levers being balanced about the pivotal axis of the balancing lever and disposed to apply a reactive force received from the corresponding contact members through the axis of the balancing lever which is opposed to the reactive pressure of the contact members transmitted through the supporting lever carrying the balancing lever whereby the pressures between the contact members are distributed from one pole to the other, and means associated with each toggle linkage to break it when the toggle linkages move with the supporting levers when any one toggle linkage is broken in response to predetermined operating conditions, and a tripping member associated with each toggle linkage.
11. In a multiple pole circuit breaker, in combination, a plurality of cooperative switch members, a toggle linkage connected to the cooperative switch members of each pole for biasing the switch members into pressure engagement, means for actuating the toggle linkages of the poles to their over-center positions to close the breaker, a tripping member associated with each toggle linkage, a pivotally mounted balancing lever, means for balancing the reactive pressures from the switch members of the different poles about the pivotal axis of the balancing lever, the balancing lever being disposed to move as a unit to effect a movement of the toggle linkages relative to the tripping members, thereby to provide for actuating the switch members of the breaker.
12. In a multiple pole circuit breaker, in combination, a plurality of cooperative switch members for each pole of the breaker, a toggle linkage connected to the cooperative switch members of each pole to actuate them, means for actuating the toggle linkages of the poles to their over-center positions to close the breaker, a tripping member associated with each toggle linkage, a pivotally mounted balancing lever, means for balancing the reactive pressures from the switch members of the different poles about the pivotal axis of the balancing lever, the balancing lever being disposed to move as a unit to effect a movement of the toggle linkages relative to the tripping members and means responsive to electrical conditions for breaking one of the toggle linkages to unbalance the reactive forces applied to the balancing lever to effect its movement as a unit and the movement of the toggle linkages relative to the tripping members to break all the toggle linkages and thereby separate all the cooperative switch members of the different poles of the breaker.

STANLEY T. SCHOFIELD.
